STOKER HOPPER SWITCH

Burton E. Shaw, Adel, Iowa, assignor to Penn Electric Switch Co., Des Moines, Iowa, a corporation of Iowa

Application April 27, 1937, Serial No. 139,251

7 Claims. (Cl. 200—52)

An object of my present invention is to provide a stoker hopper switch which is readily adaptable for mounting on the hopper of a stoker for controlling a fuel supply means.

5 A further object is to provide a switch especially adaptable for stoker hopper operation and including means responsive to the presence or absence of fuel in the hopper to control a circuit.

Another object is to provide a switch so designed that it can be readily adjusted for installation of various types, and particularly can be changed on the job from a switch which is closed when fuel is present in the hopper to one which is closed when there is an absence of fuel in the 15 hopper, or vice versa, in a facile manner.

A further object is to provide a switch particularly adaptable for hopper installation including a reversible cam and means to operate the cam including a rock shaft and a pressure plate carried thereby and extended into the hopper for operation by coaction of coal or other fuel in the hopper therewith.

With these and other objects in view, my invention consists in the construction, arrangement 25 and combination of the various parts of my stoker hopper switch, whereby the objects contemplated are attained, as hereinafter more fully set forth, pointed out in my claims, and illustrated in the accompanying drawing, in which:

30 Figure 1 is a diagrammatical sectional view through a hopper and a feed bin therefor showing my hopper switch installed for operating a fuel conveyor from the bin to the hopper.

Figure 2 is a front elevation of same looking in 35 the direction of the arrow 2 adjacent Figure 1.

Figure 3 is an enlarged sectional view on the line 3—3 of Figure 1 showing a pressure plate or blade used in connection with my hopper switch for actuating the same.

40 Figure 4 is an enlarged sectional view on the line 4—4 of Figure 2.

Figure 5 is a sectional view on the line 5—5 of Figure 4 showing the parts on a reduced scale and showing the cam of the switch mechanism 45 adjusted for operation in the circuit shown in Figure 1.

Figure 6 is a perspective view of an actuating member of my switch mechanism to which a cam member is to be secured.

50 Figure 7 is a perspective view of the cam member.

Figure 8 is a sectional diagrammatical view of a stoker with my hopper switch mounted thereon for operation in a different type of circuit; 55 and

Figure 9 is a view of the actuating member and cam of Figures 6 and 7 showing the cam reversed relative to the position shown in Figure 5 for operation in the circuit shown in Figure 8.

On the accompanying drawing I have used the reference character H to indicate a hopper of a stoker or the like, and B a bin adapted to contain coal or other fuel to be fed to the hopper H. I show diagrammatically a screw conveyor 10 for conveying the fuel from the bin B to the hopper 10 H, the conveyor being operated by a motor M.

My hopper switch includes a rock shaft 11 suitably journaled in bearings 12 attached to a wall 13 of the hopper H. The wall may be slotted as at 14 to permit the passage of a pressure plate 15 therethrough, the pressure plate 15 being secured at its outer edge to the rock shaft 11. As shown in Figure 3, the pressure plate 15 is adapted to normally assume a position spaced from the wall 13. Such position is shown by solid lines. 20

In Figure 2 I show a spring 16 for biasing the pressure plate 15 to such position, the spring being connected with a lever 17 mounted on the rock shaft 11. Whenever sufficient fuel is present in the hopper H to cover the plate 15, the 25 plate will be moved to the dotted position shown in Figure 3 against the bias of the spring 16.

I provide a switch indicated generally at S adapted to control the motor M and responsive to the movement of the shaft 11 and consequently 30 the pressure plate 15. The switch S includes a protecting casing 18 mounted as by a bracket 19 on the hopper H. Within the casing 18 a bracket 20 is provided on which is mounted a switch housing 21 having a cover plate 22.

Within the switch housing an armature 23 is 35 pivotally mounted and carries an armature 24 adapted to be attracted by a permanent magnet 25. When the armature 23 is in the position shown in Figure 4, it separates a pair of contacts 40 26 and 27 from each other, which contacts are included in the circuit of the motor M.

For actuating the armature arm 23, and thereby opening and closing the contacts 26 and 27 I provide an actuating element in the form of a 45 50 slideable pin 28. A spring 29 is interposed between this pin and the armature 23 for absorbing part of the energy which slides the pin and storing such energy for quickly moving the armature 24 from adjacent the magnet 25 and thereby separating the contact 26 from the contact 27 with snap action.

A cam C is provided for operating the pin 28. This cam has a lobe 30, an arcuate slot 32 and a hub 33. The hub 33 is mounted on a pivot pin

34 supported by the bracket 20 and is connected with an actuating lever 35. The lever 35 is likewise mounted on the pin 36 and the two are secured together by an adjusting screw 36. This 5 screw is threaded into one or the other of a pair of threaded openings 37 and 38 in the actuating lever 35. The actuating lever 35 has a slot indicated at 39 with which a pin 40 is adapted to coat. The pin 40 is carried by the 10 arm 17 secured as by a set screw 42 to the rock shaft 11.

Practical operation

In the operation of my stoker hopper switch, 15 assuming it installed as in Figures 1 and 5, it will be noted that the lobe 30 is on the right hand side in Figure 5. When the lobe coats with the actuating pin 28, the circuit of the motor M will be opened.

20 Figure 5 illustrates such coaction, which is a result of movement of the pressure plate 15 to the dotted position of Figure 3, due to the presence of fuel in the hopper H.

Thus the motor M and conveyor 10 will be 25 stopped whenever the hopper H is filled with fuel and will be started as soon as the fuel recedes in the hopper to a position below the plate 15, whereupon the spring 16 will swing the plate to the full line position and again initiate operation 30 of the conveyor 10, which will continue to operate until the hopper is again filled. The particular position of operation of the switch relative to the position of the plate 15 can be adjusted somewhat by the adjusting screw 36 and 35 arcuate slot 32.

In Figure 8 an installation is shown wherein a hopper H' is customarily fed with fuel from a source of supply including a chute 43. A motor M' operates the blower and fuel feeding mechanism of a stoker 44 and is controlled by a room 40 thermostat RT and a switch S in series.

The cam C for this installation is reversed as 45 illustrated in Figure 9 when compared with Figure 5, so that when the hopper H' has been emptied, the switch contacts 26 and 27 will be separated instead of engaged. Thus the switch S in the installation in Figure 8 serves as a safety switch to cut off the supply of current to the motor M' which is normally controlled in 50 response to room temperature, and such cut off occurs whenever the supply of fuel is exhausted or runs low in the hopper H'

This provides assurance against the blowing 55 back of coal from the stoker 44 into the hopper H' as would occur when the coal is almost completely fed into the furnace and the motor M' continues to operate, thus creating a pressure above atmospheric pressure in the furnace, stoker and hopper.

60 I have provided a switch which, it is obvious, can be readily adjusted for either of the installations shown in Figures 1 and 8, or for any other installation suitable where a pressure plate may be utilized within a hopper or the like to 65 control the switch.

It is a comparatively simple matter to remove the screw 36, for instance, from the opening 38, turn the cam C a half revolution and then reinsert the screw in the opening 37.

70 Some changes may be made in the construction and arrangement of the parts of my device without departing from the real spirit and purpose of my invention, and it is my intention to 75 cover by my claims any modified forms of struc-

ture or use of mechanical equivalents which may be reasonably included within their scope.

I claim as my invention:

1. In a stoker hopper switch, a rock shaft, a plate having one edge connected therewith, means biasing said rock shaft to rotate and project the free edge of said plate into the stoker hopper, a control switch and an operative connection between said rock shaft and said control switch, said control switch including a casing and an operating element projecting therefrom for the switch mechanism of the control switch, a movable actuator having a cam lobe coacting with said operating element.

2. In a stoker hopper switch, a rock shaft journalled on the wall of a stoker hopper, a plate having one edge connected therewith, means biasing said rock shaft to rotate and project the free edge of said plate into said hopper, a control switch and an operative connection between said rock shaft and said control switch, said control switch including a movable actuator, a cam member reversibly mounted thereon and an operating element for the switch mechanism of said control switch and coacting with said cam member in either of its reversed positions.

3. In a device of the class described, a rock shaft, a pressure plate connected thereto, a switch for operation by said rock shaft and having an operating element, a cam coacting therewith and means for actuating said cam comprising a lever and a second lever mounted on said rock shaft and having a pin and slot connection with said first lever.

4. In a device of the class described, a rock 35 shaft, a pressure plate connected thereto, a switch for operation by said rock shaft and having an operating element, a cam and an operative connection between said rock shaft and said cam, said cam comprising a disk having a lobe axially 40 displaced from the plane of the disk and coacting with said operating element to move it axially of said disk.

5. In a device of the class described, a movable pressure plate adjacent the wall of a hopper, a 45 switch for operation thereby and including a housing and an operative connection between said pressure plate and said switch for operating said switch in accordance with movements of the pressure plate in response to the pressure of fuel thereagainst in said hopper, said operative connection including a rock shaft, a lever attached thereto and terminating adjacent said housing, said switch having an operating element projecting from said housing and having a pin and 50 slot connection with said lever.

6. In a stoker hopper switch, a rock shaft, a pressure plate connected therewith, a switch having an operating element, a disk like cam for actuating said operating element and having an 60 axially displaced lobe and an operative connection between the rock shaft and said cam, said cam being reversible to place said lobe on the radially opposite side of the axis of said disk for reversing the operation of said switch in response to movement of said pressure plate.

7. In combination with a stoker hopper, a switch operable in response to the presence of fuel therein, fuel supply means controlled by said switch, said switch including a reversible cam for 70 actuating the switch mechanism thereof whereby said cam may be installed for either opening or closing the circuit of said fuel supply means in response to the presence of fuel in said hopper.

BURTON E. SHAW. 75
